DESIGN FOR A COMBINED WRENCH AND PLIERS

William R. Payne, Chesapeake, W. Va.

Application November 24, 1942, Serial No. 108,863

Term of patent 14 years

To all whom it may concern:

Be it known that I, William R. Payne, a citizen of the United States, residing at Chesapeake, in the county of Kanawha and State of West Virginia, have invented a new, original, and ornamental Design for a Combined Wrench and Pliers, of which the following is a specification, reference being had to the accompanying drawing, forming part thereof.

The figure is a view in perspective of a combined wrench and pliers embodying my new design.

I claim:

The ornamental design for a combined wrench and pliers, substantially as shown.

WILLIAM R. PAYNE.
